(57) **CLAIM**

The ornamental design for a ratchet coupler for screw driver, as shown and described.

DESCRIPTION

FIG. 1 is a perspective view of a ratchet coupler for screw driver showing my new design;

FIG. 2 is a front elevational view thereof; (the rear; left; right views are the same as the front elevational view)

FIG. 3 is a top plain view thereof;

FIG. 4 is a bottom plain view thereof; and,

FIG. 5 is a perspective view thereof, wherein the broken line showing of the ratcheting screw driver is for illustrative purposes only and forms no part of the claimed design.
